UNITED STATES PATENT OFFICE.

EINAR MINGE, OF CHICAGO, ILLINOIS.

PRIMING CUP FOR INTERNAL-COMBUSTION ENGINES.

Application filed December 16, 1920. Serial No. 431,161.

To all whom it may concern:

Be it known that I, EINAR MINGE, a former subject of the King of Norway, who has foresworn his allegiance to said King of Norway and declared his intention of becoming a citizen of the United States, and a resident of the city of Chicago, county of Cook, and State of Illinois, have invented certain new and useful Improvements in 10 Priming Cups for Internal-Combustion Engines, of which the following is a specification.

My invention relates to improvements in priming cups for internal combustion engines, and more particularly to the means for priming the same, the object of the invention being to provide a simple and convenient means for priming and facilitating the starting and operation of internal combustion engines.

Other objects will appear hereinafter.

The invention consists in the combinations and arrangements of parts hereinafter described and claimed.

The invention will be best understood by reference to the accompanying drawings forming a part of this specification, and in which,

Fig. 1 is a side view of a priming cup embodying the invention,

Fig. 2, a vertical section of the same,

Fig. 3, a view similar to Fig. 1 but showing the valve open,

Fig. 4, a detail section of a valve stem head employed in the construction,

Fig. 5, a section through the head of an internal combustion engine cylinder showing the priming cup in position of use,

Fig. 6, a view of a slightly modified form 40 of valve stem.

The preferred form of construction, as illustrated in Figs. 1 to 5 inclusive, comprises a priming cup 7 having a threaded stem 8 adapted and arranged to be threaded 45 in a suitable threaded opening leading into the engine cylinder 9, as indicated. The engine cylinder 9 is equipped with the usual piston 10 and connected with the usual connecting rod 11, as indicated. The priming 50 cup 7 is provided with a central bore or passage leading centrally from the bottom thereof through the stem 8 and into the cylinder 9 and a hollow valve stem 12 is arranged in said passage and projects upwardly into said 55 cup. The lower end of the valve stem 12 is closed by valve head 13 seated on the valve

stem 8. At its upper end, the valve stem 12 carries two lock nuts 14 threaded thereon and serving as a stop to imprison a compression spring 15 between said nuts and the 60 bottom of cup 7 and whereby the valve head 13 is yieldingly held to its seat to close the communication between the cup 7 and the cylinder. Suitable openings or ports 16 are provided in the stem 12 just above the valve 65 head 13 whereby air may pass through said valve stem into the cylinder when the valve is open, as indicated in Fig. 3.

In operation, the priming cup is secured in the head of the cylinder, substantially as 70 indicated in Fig. 5, and is supplied with a priming charge of gasoline or the like. Upon the suction stroke of the piston 10, the valve 13 will be automatically opened by said suction and the priming charge of gasoline mixed with air drawn into the cylinder. 75 Upon the compression stroke of the piston 10, the valve 13 will be automatically closed by the combined action of the spring 15 and the compression within the cylinder. 80 Thus a rich priming mixture will be automatically drawn into the cylinder thus greatly facilitating the starting of the engine. During the normal running of the engine, the valve 13 will open at each suction stroke of the piston, thus admitting a 85 small quantity of fresh air which will aid the normal operation of the engine.

In the modified form of valve stem, illustrated in Fig. 6, the valve stem 12 is provided with one or more longitudinal slots 17 positioned at the bottom of the cup 7 and with a slightly different form of opening 18 at its inner end. By this arrangement, some of the priming charge of gasoline will pass 95 into the hollow interior of the stem 12 thus mixing with the air passing into said hollow stem and thus tending to provide a more perfect explosive mixture. Otherwise the construction and operation is the same as 100 that already described.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 110 the appended claims.

Having described my invention, what I

claim as new and desire to secure by Letters Patent is:—

1. In a priming cup, the combination of a stem having a passage leading from said cup into the cylinder of an internal combustion engine for the passage of fuel from said cup into said cylinder; an upwardly yielding spring-held hollow valve stem mounted in said passage and extending into said cup there being openings in said valve stem for the admission of air into said cylinder; a valve seating formed on the inner end of said valve stem normally closing the passage between said cup and cylinder; substantially as described.
2. In a priming cup, the combination of a stem having a passage leading from said cup into the cylinder of an internal combustion engine; a hollow valve stem arranged

in said passage adapted to move downwardly upon a suction stroke of the piston of said cylinder, there being a T shaped opening adjacent the inner end of said valve and an elongated slot above said T shaped opening for the admission of air into said cylinder when said valve is moved downwardly; and a valve seat formed on the inner end of said valve stem normally closing the passage between said cup and cylinder, substantially as described.

In testimony whereof I have signed my name to this specification in the presence of two subscribing witnesses.

EINAR MINGE.
